[57] CLAIM

The ornamental design for a remote control cover, as shown and described.

DESCRIPTION

FIG. 1 is a perspective view of a remote control cover, showing my new design, the broken line showing of a remote control is for illustrative purposes only, and forms no part of the claimed design;

FIG. 2 is a top plan view of the remote control cover unfolded form around the remote control;

FIG. 3 is a bottom plan view of the unfolded remote control cover of FIG. 2;

FIG. 4 is a left side elevation view thereof, the right side elevation view being a mirror image thereof;

FIG. 5 is a forward end elevation view thereof, the rear end elevation view being a mirror image thereof; and,

FIG. 6 is a reduced perspective view like that of FIG. 1, less the T.V./VCR remote control.
